(57) **CLAIM**

The ornamental design for an articulating connector, as shown and described.

DESCRIPTION

FIG. 1 is an isometric view of an articulating connector showing my new design.

FIG. 2 is a front plan view thereof.

FIG. 3 is a right side plan view thereof.

FIG. 4 is a left side plan view thereof.

FIG. 5 is a top plan view thereof.

FIG. 6 is a bottom plan view thereof; and,

FIG. 7 is a rear plan view thereof.

The broken line showing of additional parts and accessories is for illustrative purposes only and forms no part of the claimed design.
